US00D749215S

(12) **United States Design Patent**
Ahluwalia et al.

(10) **Patent No.:** **US D749,215 S**
(45) **Date of Patent:** **** Feb. 9, 2016**

(54) **MEDICAL DEVICE**

(71) Applicants: **Prabhat Kumar Ahluwalia**, Little Falls, NY (US); **Puja Ahluwalia**, Little Falls, NY (US)

(72) Inventors: **Prabhat Kumar Ahluwalia**, Little Falls, NY (US); **Puja Ahluwalia**, Little Falls, NY (US)

(**) Term: **14 Years**

(21) Appl. No.: **29/517,272**

(22) Filed: **Feb. 11, 2015**

Related U.S. Application Data

(63) Continuation-in-part of application No. 14/604,692, filed on Jan. 24, 2015, which is a continuation of application No. 14/204,766, filed on Mar. 11, 2014.

CLAIM

The ornamental design for a medical device, as shown and described.

DESCRIPTION

FIG. 1 is a perspective view of a medical device showing our new design;

FIG. 2 is a second perspective view of a medical device shown in FIG. 1;

FIG. 3 is a front view of the medical device shown in FIG. 1; FIG. 4 is a rear view of the medical device shown in FIG. 1; FIG. 5 is a side view of the medical device shown in FIG. 1; FIG. 6 is a top view of the medical device shown in FIG. 1; FIG. 7 is a perspective view of the medical device shown in FIG. 1;

FIG. 8 is a perspective view of the medical device shown in FIG. 1; and,

FIG. 9 is a perspective view of the medical device shown in FIG. 1.

Elements shown in broken lines show environmental structures or non-claimed portions of the medical device and form no part of our design.

1 Claim, 4 Drawing Sheets
